ADJUSTABLE X-RAY APPARATUS

Charles P. Davis, Jr., Robert L. Guentner, Robert J. Wagner, and Everett W. Vaughn, Baltimore, Md., assignors to Westinghouse Electric Corporation, East Pittsburgh, Pa., a corporation of Pennsylvania

Application May 29, 1948, Serial No. 30,096

10 Claims. (Cl. 250—57)

1

This invention relates to X-ray apparatus and, more particularly, to an adjustable table with facilities for vertical and horizontal fluoroscopy, as well as vertical and horizontal radiography.

The principal object of our invention, generally considered, is to provide an apparatus for use in vertical and horizontal fluoroscopy in addition to vertical and horizontal radiography, without requiring the interchanging of the relative positions of the X-ray tube and fluoroscopic screen with respect to the patient-supporting table.

Another object of our invention is to provide a single tube X-ray table with two operating surfaces, one for fluoroscopy with the patient between the surface and the fluorescent screen, and one for radiography with the patient between the surface and the tube head, with a film in a cassette associated with a Bucky diaphragm inside of the table.

A further object of our invention is to provide an adjustable X-ray table of the hand-rocked type, counterbalanced for ease of operation for 180° range from horizontal through vertical to the opposite horizontal position, whereby it is unnecessary to use more than one X-ray tube and one fluorescent screen, and the relative positions of these parts need not be shifted.

A still further object of our invention is to provide an adjustable X-ray table having a counterbalanced longitudinal carriage carrying a cross-carriage on which the screen and tube are mounted, said table being reversible through 180° to make it unnecessary to shift the relative positions of the screen and tube, a latch being provided for holding the table in adjusted position, a self-locking crank being provided for moving the Bucky diaphragm, and the screen being provided with a three-position device useable to let the screen operate freely for vertical fluoroscopy, to have the screen balanced for use in horizontal fluoroscopy, or with the screen locked to prevent dropping on the floor for use in horizontal radiography.

Other objects and advantages of the invention, relating to the particular arrangement and construction of the various parts, will become apparent as the description proceeds.

Referring to the drawing:

Figure 1 is a side elevational view of our table adjusted for horizontal radiography.

Figure 2 is a side elevational view of our table adjusted for vertical radiography.

Figure 3 is a side elevational view of our table adjusted for horizontal fluoroscopy.

Figure 4 is a side elevational view of our table adjusted for vertical fluoroscopy.

2

Figure 5 is an end elevational view of the table as illustrated in Figure 3.

Figure 6 is an end elevational view of the table as illustrated in Figure 1.

5 Figure 7 is an enlarged fragmentary side elevational view of the table in the position of Figure 1, with parts in vertical section on the line VII—VII of Figure 10, in the direction of the arrows.

10 Figure 8 is an enlarged fragmentary side elevational view, with parts in vertical section on the line VII—VII of Figure 10, in the direction of the arrows, of the table in diagonal or tilted position, in the process of being moved between the position of Figure 1 and that of Figure 2.

15 Figure 9 is an enlarged fragmentary side elevational view, with parts in vertical section on the line VII—VII of Figure 10, in the direction of the arrows, of the table in the position of Figure 2.

20 Figure 10 is an enlarged fragmentary vertical sectional view, on the line X—X of Figure 9 in the direction of the arrows, parts being shown in elevation.

25 Figure 11 is an enlarged fragmentary side elevational view, with parts in vertical section on the line VII—VII of Figure 10, of the table positioned as in Figure 3.

30 Figure 12 is a fragmentary side elevational view, with parts in axial section, of the screen counterbalancing spring assembly and X-ray tube adjusting arm.

35 Figure 13 is a set of transverse sectional views, the upper elements of which illustrate the knob, pointer, and dial assembly in different positions viewed from the top of Figure 12, while the corresponding views, immediately therebelow show, first, sections on the line A—A of Figure 12, and then, sections on the line B—B of Figure 12, in order to illustrate what the various pointer adjustments mean as to the position of the index rod and its relationship with the spring-confining plates.

40 Figure 14 is a fragmentary axial view, on the line XIV—XIV of Figure 12, in the direction of the arrows.

45 Figure 15 is a fragmentary axial sectional view, on the line XV—XV of Figure 12, in the direction of the arrows.

50 Figure 16 is a transverse vertical sectional view on the line XVI—XVI of Figure 17 in the direction of the arrows, showing in elevation the crank for moving the Bucky diaphragm.

55 Figure 17 is a longitudinal sectional view on the line XVII—XVII of Figure 16, in the direction of the arrows.

Figure 18 is a fragmentary plan on the line XVIII—XVIII of Figure 16 in the direction of the arrows.

Figure 19 is a fragmentary elevational view, with parts in section, corresponding to Figure 17, but showing how the movement of the crank unlocks the spring in moving the Bucky.

Figure 20 is a detailed axial view of the locking spring.

Figure 21 is a view in perspective of a portion of the operating crank and the spring-releasing segment on its shaft.

Figure 22 is a perspective view of the operating pinion and its locking segment.

Apparatus providing for both vertical and horizontal fluoroscopy as well as vertical and horizontal radiography are not unknown in the X-ray art. However, it has heretofore been necessary to either use two X-ray tubes, one for radiography and the other for fluoroscopy, or use one X-ray tube so mounted so that it can be moved from a position above the X-ray table for radiography, to a position beneath said table for fluoroscopy.

The X-ray table of the present invention uses only one X-ray tube for both radiography and fluoroscopy, and differs from previous designs in that it tilts from a horizontal position, such as shown in Figure 1, through a vertical position, such as shown in Figure 2, to the reverse horizontal position, shown in Figure 3, rotating a total of 180°. This feature of tilting 180° makes it unnecessary to shift the X-ray tube from above the table to beneath the table, while switching from radiography to fluoroscopy, as in our X-ray table both the initially top surface, and that which is then the bottom surface of the table, are used as operating areas.

Considering a preferred embodiment of our invention, in a general way it includes, a three-position hand-rock tilt table 21, desirably about 75½" long by 28" wide and not more than 10¾" thick, the frame of which is constructed of steel of sufficient section to insure rigidity when in a horizontal position and carrying a 200 pound patient. The table is provided with rails 70 within the body thereof to slidably guide shoes 90 carried by the housing of a Bucky diaphragm 22 for adjustably supporting the latter. The Bucky 22 holds the cassette and its photographic film, and when installed, faces the side of the table 21 at which the X-ray tube 23 is mounted, said Bucky not being counterweighted. The table body desirably contains fixed lead or steel counterweights 24, so that tilting it will require a pull not greater than 30 pounds, it being noted that the pivot axis 25 for the table is not equidistant from the ends of the latter.

Inside the table is a longitudinally-movable carriage 26, desirably counterweighted as indicated at 110, connected thereto by steel balls 27 between its edges and corresponding tracks near the sides of the table. Mounted on said longitudinally-movable carriage, is a transversely-movable carriage 28 which may include a shutter (not shown). It is correspondingly mounted for free movement in tracks attached to said longitudinally movable carriage. The longitudinal movement is desirably about 27" and the transverse movement desirably about 8".

A latch 29, shown in detail in Figures 7 to 11, inclusive, slidable on guide and stop block 43, is provided for holding the table 21 in adjusted position with respect to the base 31, which in the present embodiment is formed by legs 32 and 33. The table is pivoted to said legs by bolts 34 and

35 received in spherical bushings 36 and 37, adjustably carried in bearings 38 and 39 in the legs 32 and 33, respectively. The bolt 34 passes outwardly from the inner side of the table side wall 51, through reinforcing plate 42, bolted to said side wall, and block 43 welded to said plate, through latch 29 and bushing 36. It has its end received in nut means 44. The pocket receiving the nut means, which may involve two nuts for locking purposes, is desirably closed by a cap 45. The bearing 38 is held in place in leg 32, by plate 39 secured by screws.

The other pivot bolt 35 passes from the outside into leg pocket, which is finally closed by cap 20, through bushing 37, retainer plate 46 held to leg 33 by screws 47, washer 48, and the reinforcing plate 49 desirably welded to side wall 51 of table 21.

The latch 29 is controlled by release knob 54, through connecting rod 55 which is normally urged into locking position by means of coil compression spring 56 thereon, acting between a collar 57 fixed on the rod and a stop and guide 58 mounted on the inner surface of the side wall 51 of the table 21. The other end portion of the rod moves in a guide 59. The latch 29 has a slot 61 through which the bolt 34 and a guide lug 40 on the stop block 43 passes, while held in guiding relation therewith by plate 50 secured to said lug by screws 60, allowing movement by the release knob 54 from latched position, shown in Figure 7, to unlatched position shown in Figure 8, where the prong 62 of the latch 29 has been withdrawn from the shoulder 63 on the leg 32. This permits the table to be tilted or moved clockwise or in the direction of the arrow 64 only, counterclockwise rotation being prevented by the engagement between the stop block rib 70 and the shoulder 63 of the leg 32 on the one side, and the adjusted stop screw 53 and the abutment portion 144 on the leg 33 on the other, to the position represented in Figure 8 from whence it is free to be returned or moved to the position represented in Figure 9 where, if the knob 54 is released, the latch will drop to the locking position there represented, where its prongs 62 and 65 straddle the shoulder or lug 66 on the leg 32, to thereby hold the table locked in vertical position.

Upon again releasing the knob 54, by pulling in the direction of the arrow 67, the latch 29 is withdrawn from the lug 66, allowing the table to be tilted further until finally the position represented in Figure 11 is reached where further movement is prevented by engagement between the rib 70 and the shoulder 68, on the one side, and the adjusted stop screw 145 and the abutment portion 144 on the other, and the latch 29 has snapped over said shoulder 68, with its prong 65 positioned in locking engagement therewith. This prevents return movement of the table 21 until the index latch is again released by corresponding movement of the control knob 54.

Referring now to the cross carriage screen arm and tube arm assembly, illustrated in Figures 12 to 15, inclusive, there is shown the details of the mechanism which adjustably carries the X-ray tube 23 and fluorescent screen 69. This assembly, represented generally by the reference character 74, comprises a hollow metal cylinder or tube 72, preferably formed of steel, and mounted on the transversely-movable carriage 28, so as to stand vertical when the table is horizontal, as in the position of Figures 1, 3, 5, and 6, and horizontal when the table is vertical, as in the position of Figures 2 and 4.

Inside of the cylinder 72 is a compression spring 73, confined between plate 74, which may consist of two pieces secured together, and plate 75, the latter of which rests on a spacer tube 76 held in place in cylinder 72 by screws 77, and with its outer end closed by a cover plate 78. The latter is secured to a spring adjusting plate 79, by bolt 81, the outer end of which is finally covered by nut 143. Plates 74 and 75 appear respectively as upper and lower members of the spring adjusting assembly in Figure 12, which corresponds with the table position of Figures 3 and 5 for horizontal fluoroscopy, but the assembly is of course reversed when the table is turned over for horizontal radiography, as in Figures 1 and 6.

The spring 73 is held under the desired compression by being urged against the plate 75 by the adjusting rods 82 and 83 threaded into the plate 74 to the desired extent, as illustrated in Figure 15, and carrying threaded ends to which nuts 84 and 85 are applied, after they are passed through apertures in plate 79. The bolt 81 has a head which may serve as a limit stop against downward movement of the index rod 86, which controls the operation of the screen supporting arm 87 in accordance with the angular position thereof, determined by the location of the pointer 88 on the control knob 89. The latter is non-rotatably secured to the "upper" end of the rod 86, as by means of pin 91, and movable with the rod and pointer over dial 92 for positioning in any one of three positions.

The rod 86 carries a pin 93, shown as "upper" in Figure 12, and a pin 94, shown as "lower" in said figure, adapted to engage the adjacent plates 74 and 75, respectively, or pass through slots 95 and 96 in the plate 74, 97 in the plate 75, or move in safety guide 98 projecting from said plate 75. The ends of the safety guide 98 project different distances through the carrying plate 75, forming a long safety stud 80 to prevent more than 120° rotation of the rod 86, and a short safety stud 105 to prevent the pointer 88 and rod 86 from being turned from position #3 to position #1 without first releasing said index rod from force of spring 73.

The screen-arm-end of the tube 72 carries a cap 99, through a slot 100 in which passes index rod 86. Bearing lugs 101 project from the cap 99, and between them is pivoted the screen arm 87, as by means of pivot pin 102. The extreme end of the screen arm 87 is pivoted to the index plate block 103, rotatably mounted on the rod 86 and to which the dial 92 is secured. Engagement between the block 103 and cap 99 may be resiliently prevented by spring 104, confined against the block 103, as by pin 146 through rod 86 and washer 147; or non-resiliently by a collar mounted on rod 86 and locked in the desired position by a setscrew (not shown). By virtue of the described arrangement, the screen arm 87 may alternatively be released from the spring for free movement, in connection with vertical fluoroscopy, have its weight balanced by the spring, as for use in horizontal fluoroscopy, or be "locked" for use in horizontal radiography.

The screen 69 is freed from the action of the spring 73 by turning the knob 89 and its pointer 88 to position #1, represented in Figure 13 by the views in the left column. In this position the index rod 86 will travel freely along its axis, because its pin 94 slides in the safety guide 98, and moves without opposition through slot 97 in plate 75, while the pin 93 likewise moves freely

without opposition through slot 95 in plate 74, rotation of the rod 93 being prevented during the entire range of screen travel by said safety guide.

In order to change the action of the spring 73, from one where the screen 69 is free thereof to one where it is balanced thereby, the screen 69 is pulled away from the table 21, as from position shown in dotted lines in Figure 5 to that in full lines thereof, causing the index rod 86 to travel into cylinder 72 until, at the extreme end of travel, index pin 94 is not only through plate 75 but clears the end of safety stud 105, whereupon the pointer 88 is turned to position #2 on the dial 92, and the parts left in the position shown in the middle views of Figure 13. Here the pin 94 is in engagement with the "bottom" or outer surface of plate 75. The index pin 93, however, is then between the plates 74 and 75, but free to move through the slot 96 in the plate 74. This means that downward movement of the screen, as from the full line position in Figure 5 to the dotted line position in said figure, is resiliently opposed or balanced by compression of the spring 73 against the plate 74, by movement of the plate 75 toward it by corresponding pressure of the pin 94 on the bottom of said plate 75 as the rod 86 moves "upwardly."

The locked position, where the screen is held off the floor when the table 21 and parts carried thereby are reversed, as represented in Figure 6, is obtained by moving the pointer 88 to position #3 on the dial 92, where the positions of the pins 93 and 94 are represented in the views in the right hand column of Figure 13. This position is entered from that of position #2, shown in the middle column of Figure 13. The index pins 93 and 94 are so set in the rod 86 that when the screen is pushed toward the table, passing its midpoint of travel, index pin 93 just passes through plate 74. Then, turning the knob 89 so that the pointer 88 moves from position #2 to position #3 on dial, the spring 73 is confined to a short length by the pin 93 engaging the "top" of the plate 74, and the pin 94 engaging the "bottom" of the plate 75, thereby placing the spring under an extra amount of compression, and making it sufficiently rigid to hold the screen substantially horizontal above the table, when in the position represented in Figure 3. When the table 21 is turned to the position represented in Figure 6, the screen is held in a substantially horizontal position and prevented from dropping on the floor by force transmitted to block 103, through rod 86, pin 93, plate 74, bolts 82 and 83, from plate 78. Plate 78, in turn, receives this force through bolt 81, and plate 79 to which said bolt is secured as by welding, from spacer 76, to which plate 79 is also secured as by welding, and through securing screws 77 to column 72.

The X-ray tube 23 is carried by arm 106, the outer end of which is pivoted to a member 107 which encircles the "lower" end, as in Figure 12, of the tube 72, and is adjusted by mechanism 108 consisting of a jack screw 111 carrying a swivel nut 112, pivoted between arms 113 and 114 on tube arm 106, a thrust bearing 115 and a thrust collar 116, between which are mounted a pivoting abutment device 117, also pivoted in a bracket 118 secured to the column 72. The outer end of the jack screw 111 carries a crank and handle assembly 119, non-rotatably mounted thereon, as by means of a pin 121. The other end portion of the jack screw 111 carries locking limit nuts 122 and 123, on one side of the nut, 112, and

locking limit nuts 147 and 148 on the other side, while the extreme end carries a washer 124, a lock washer 125, and a screw 126 holding them in place. It will thus be seen that turning of the handle 127 of the assembly 109 effects raising or lowering of the arm-supported tube 23, depending on the direction of turning.

Referring now to Figures 16 to 22, inclusive, there is shown the mechanism for moving the Bucky diaphragm 22. To the end wall 128 of said Bucky is secured a supporting and spring-housing bracket 129, providing bearing 131 for the crank shaft 132, and bearing 133 for pinion 134. The pinion 134 carries a locking segment 135, while the crank shaft 132 carries a releasing segment 136, both of which segments are, when assembled, encircled by coil locking spring 137, having radial end portions 129 and 130, housed in a portion 140 of the support bracket 129, and slightly larger in free outside diameter than that of the bore of the housing portion 140. The radial spring portions are disposed between the segments 135 and 136. A force or torque on the pinion 134, in either direction of rotation, will cause the locking segment 135 to engage one of said end portions and tend to turn the spring in a direction to increase its diameter. Since the spring is confined it cannot expand, and because of the initial pressure on its outside surface, it resists turning like a differential band brake working internally. This prevents the Bucky from unintentionally moving one way or the other, whereby it is locked with respect to a pinion-engaged rack 138. The lower surface of said rack is engaged by roller 139.

This lock against Bucky movement is released by turning the crank handle 141 on the end of shaft 132 in either direction, causing the crank shaft release segment 135 to engage one of the spring end portions 129 and 130 and wind up the spring, as represented most clearly in Figure 19, thereby slightly decreasing its diameter and releasing the pressure, only one coil at a time, until the spring resisting friction is small enough to be readily overcome. It will be seen that, while the connections could be reversed, in this embodiment the drive assembly is attached to the Bucky, and the rack 138 to the chassis of the table, to be engaged by the drive pinion 134, whereby the weight of the Bucky appears as torque exerted on the spring lock. The roller 139 and associated washer 142 prevent disengagement of the rack and pinion.

From the foregoing, it will be seen that we have provided an X-ray table which is not only adjustable for use in horizontal or vertical position, but in which provision is made for the ready handling of the X-ray tube, fluoroscopic screen, and Bucky, as well as insuring that the table is securely locked in the desired horizontal or vertical position.

Although preferred embodiments of our invention have been disclosed, it will be understood that modifications may be made within the spirit and scope of the appended claims.

We claim:

1. In X-ray apparatus, a base, a table pivoted on said base and swingable 180° so as to lie horizontally, while exposing one side or the other, or stand in a vertical plane, thereby adapting it for horizontal or vertical fluoroscopy and horizontal or vertical radiography, a carriage movable longitudinally in tracks attached to the sides of said table, a second carriage movable transversely in tracks attached to said longitudinally

movable carriage, a fluorescent screen, a supporting arm extending from said screen, a screen counter-balancing spring assembly secured to said arm, and means supporting said screen, arm and spring assembly from said second carriage.

2. In X-ray apparatus, legs with stop shoulders, a table pivoted on said legs and swingable 180°, so as to lie horizontally while exposing one side or the other, or stand in a vertical plane, thereby adapting it for horizontal or vertical fluoroscopy and horizontal or vertical radiography, and means for locking said table in any one of said three positions, said means comprising a stop block secured to a side of said table, having an abutment portion projecting outwardly and swingable with said table through 180° between said stop shoulders, a latch slideable on said stop block, an operating rod secured to said latch, a collar on said rod, a control knob on the far end of said rod, guide means on said table for said rod, a locking spring mounted on said rod and compressed between one of the said guide means and said collar to bias the latch toward locking position, said latch having projections one of which engages one of said stop shoulders when in one horizontal portion, and the other of which engages a second of said stop shoulders when in the other horizontal position, while both straddle another of said stop shoulders when the table is in vertical position, whereby said table may be locked in any one of the three desired positions.

3. In X-ray apparatus, a base, a table pivoted on said base and swingable 180° so as to lie horizontally while exposing one side or the other or stand in a vertical plane, support means on said table for an X-ray tube and an associated fluorescent screen, a screen counterbalancing assembly mounted on said support means and comprising a hollow column, a compression spring enclosed in said column, means confining and adjusting the compression of said spring, a rod movable in said spring and carrying index pins, the means confining said spring being slotted, one of said means carrying a guide for one of said pins, means pivotally mounting said arm intermediate its ends with respect to said column, a collar rotatable on said rod, a knob and pointer assembly secured to the end of said rod beyond said collar, means pivotally connecting the extreme end of said arm to said collar, said knob serving to turn said rod to adjust its relation with respect to said slotted spring-confining means, whereby the screen may be released from said spring and adapted to move freely for use in vertical fluoroscopy, balanced by said spring for use in horizontal fluoroscopy, or locked to prevent it dropping on the floor when the apparatus is used for horizontal radiography.

4. In X-ray apparatus, a base, a table pivoted on said base and swingable 180° so as to lie horizontally, while exposing one side or the other, or stand in a vertical plane, thereby adapting it for horizontal or vertical fluoroscopy and horizontal or vertical radiography, a carriage movable longitudinally in tracks attached to the sides of said table, a second carriage movable transversely in tracks attached to said longitudinally movable carriage, a fluorescent screen, a supporting arm extending from said screen, a screen counterbalancing spring assembly comprising a hollow cylindrical column mounted on said transversely movable carriage, a compression spring enclosed in said column, means confining and adjusting the compression of said spring, a rod movable in said spring and

carrying index pins, the means confining said spring being slotted, one of said means carrying a guide for one of said pins, means pivotally mounting said arm intermediate its ends to said column, a collar rotatable on said rod, a knob and pointer assembly secured to the end of said rod beyond said collar, the adjacent end of said arm being pivotally connected to said collar, and said knob serving for turning said rod to adjust its relation with respect to said compression spring, whereby the screen may be; released from said spring and adapted to move freely for use in vertical fluoroscopy, by positioning said knob so that one of said pins moves in its guide and the other passes freely through slots in the adjacent confining means; balanced by said spring for use in horizontal fluoroscopy, by positioning said knob so that one of said pins engages one of said confining means while the other pin passes freely through the other confining means; or locked to prevent it dropping on the floor when the apparatus is used for horizontal radiography, by positioning said knob so that each pin engages the outer surface of the adjacent confining means.

5. In X-ray apparatus, a support, a fluorescent screen, a supporting arm extending from said screen, a screen counterbalancing spring assembly comprising a hollow cylindrical column mounted on said support, a compression spring enclosed in said column, a rod movable in said spring and carrying index pins, plates engaging the respective ends of said spring for confining the same, means acting on one of said plates for adjusting the compression of said spring, both of said plates being slotted and one carrying a guide for one of said pins, means pivotally mounting said arm intermediate its ends on said column, a collar rotatable on said rod, a knob and pointer assembly secured to the end of said rod beyond said collar, the adjacent end of said arm being pivotally connected to said collar and said knob serving for turning said rod to adjust its relation with respect to said spring, whereby said screen may be; released from said spring and adapted to move freely for use in vertical fluoroscopy, by positioning said knob so that one of said pins moves in said guide and the other passes freely through slots in the other plate; balanced by said spring for use in horizontal fluoroscopy, by positioning said knob so that one of said pins engages the plate which is not acted on by said adjusting means while the other pin passes freely through slots in the other plate; or locked to prevent it from dropping on the floor when the apparatus is used for horizontal radiography, by positioning said knob so that one of said pins engages the plate, which is not acted on by said adjusting means, on its outer surface, while the other engages the other plate, also on its outer surface, without making use of any of said slots.

6. In X-ray apparatus, support means, an X-ray tube mounted on said support means, and adjustment means for said tube comprising an arm one end of which is secured to said tube and the other end of which is pivoted to said support means, said arm having means in which a nut is swiveled, a jack screw threaded through said nut, means holding against longitudinal movement while allowing turning of another portion of said jack screw with respect to said support, and means for turning said screw to adjust the angularity of said arm with respect to said support.

7. In X-ray apparatus, a base, a table pivoted on said base and swingable 180° so as to lie horizontally while exposing one side or the other or stand in a vertical plane, support means mounted on said table, an X-ray tube mounted on said support means, and adjustment means for said tube comprising an arm one end of which is secured to said tube and the other end of which is pivoted to said support means, said arm having lateral projections between which is swiveled a nut, a jack screw threaded through said nut, means pivotally holding another portion of said jack screw with respect to said support, and a crank for turning said screw to adjust the angularity of said arm with respect to said support.

8. In X-ray apparatus, a table, a Bucky diaphragm mounted to move longitudinally in said table, a bracket, a crank with a shaft mounted in said bracket, said shaft having an unlocking segment, a pinion pivoted on said shaft and carrying a locking segment, a coil spring encircling and with radial end portions disposed between said segments and frictionally housed in said bracket, a rack engaged by said pinion, one of said bracket and rack being mounted on the Bucky and the other on said table, and a roller engaging said rack to insure meshing of it with said pinion, whereby turning of said crank in either direction acts on one of said end portions, releases said spring, and allows corresponding movement of the Bucky, while said Bucky is locked against unintentional movement by the spring binding in its housing and made tighter by engagement of the locking segment with an end portion thereof.

9. In X-ray apparatus, a base, a table on said base, a Bucky diaphragm mounted to move longitudinally in said table, and means for simultaneously preventing undesired movement of said Bucky, while allowing for desired longitudinal adjustment thereof, comprising a bracket secured to one end of said Bucky, a crank with a shaft mounted in said bracket, said shaft having an unlocking segment, a pinion pivoted on said shaft and carrying a locking segment, a coil spring encircling, and with radial end portions disposed between, said segments and frictionally housed in said bracket, and a rack mounted on said table and engaged by said pinion, whereby turning of said crank in either direction acts on one of said end portions, releases said spring, and allows corresponding movement of the Bucky, while said Bucky is locked against unintentional movement by the spring binding in its housing and made tighter if a locking segment presses on an end portion thereof.

10. In X-ray apparatus, a base, a table pivoted on said base and swingable 180° so as to lie horizontally one way or the other or stand in a vertical plane, a Bucky diaphragm mounted to move longitudinally in said table, and means for simultaneously preventing undesired movement of said Bucky, while allowing for undesired longitudinal adjustment thereof, comprising a bracket secured to one end of said Bucky, a crank with a shaft mounted in said bracket, said shaft having an unlocking segment, a pinion pivoted on said shaft and carrying a locking segment, a coil spring encircling, and with radial end portions disposed between, said segments and frictionally housed in said bracket, a rack mounted on said table and engaged by said pinion, and a roller engaging said rack to insure meshing of it with said pinion, whereby turning of said crank in either direction acts on one of

11

said end portions, releases said spring, and allows corresponding movement of the Bucky, while said Bucky is locked against unintentional movement by the spring binding in its housing and made tighter if a locking segment presses on an end portion thereof.
